[57] **CLAIM**

The ornamental design for a container for liquids, substantially as shown and described.

DESCRIPTION

FIG. 1 is an exploded elevational view of a container for liquids showing my new design;

FIG. 2 is an elevational view in a closed position, the opposite side being the same in appearance;

FIG. 3 is a top plan view;

FIG. 4 is a bottom plan view thereof; and

FIG. 5 is a fragmentary sectional view taken on the line 5—5 of FIG. 1.

FIG. 1

FIG. 2

FIG. 3

FIG. 4

FIG. 5
